UNITED STATES PATENT OFFICE.

CHARLES E. HERSHBERGER, OF LURAY, VIRGINIA.

CURRYCOMB.

SPECIFICATION forming part of Letters Patent No. 698,946, dated April 29, 1902.

Application filed March 6, 1902. Serial No. 96,925. (No model.)

To all whom it may concern:

Be it known that I, CHARLES E. HERSHBERGER, of Luray, in the county of Page and State of Virginia, have invented a new and useful 5 Improvement in Currycombs, of which the following is a specification.

My invention is in the nature of an improvement in currycombs designed to enable the face of the currycomb to better conform to 10 the curved outlines of the horse and designed also to permit of the ready cleaning of the teeth of the currycomb from the accumulated mats of loose hair and dirt; and it consists in 15 the peculiar construction and arrangement of the currycomb for accomplishing these objects in a simple and convenient way, which I will now proceed to describe with reference to the drawings, in which—

Figure 1 is a side view of the currycomb as 20 held in the hand of the hostler. Fig. 2 is a longitudinal section, and Fig. 3 an inner face view.

In the drawings, A A' represent the two 25 wings of the currycomb, which are hinged together upon a pintle-rod B, arranged at right angles to the parallel rows of the currycomb-teeth a, which are formed, as usual, on the edges of sheet-metal flanges.

C is a bowed handle strap or loop, which is 30 pivotally hung at its ends upon the ends of the pintle-rod B outside of the edges of the currycomb. This handle-strap is designed to receive the hand of the hostler, as seen in Fig. 1, and it not only serves as a handle to hold

35 the currycomb by, but it also acts as a back-rest or fulcrum for the hand in bending the currycomb-wings inwardly against springs from a straight plane to an obtuse angle in adapting it to the curved outlines of the horse.

40 Lying upon each wing of the currycomb between the flanges and below the level of the teeth there are two cleaner-grids D and D'. These consist of bent wire, each bar of which lies close to the flange bearing the teeth. 45 These grids lie normally back of the line of the teeth, but are arranged to be projected beyond the teeth outwardly to strip from the teeth the adhering mats of hair and dust for cleaning the same. For this purpose the two 50 cleaner-grids are separately hinged upon the pintle-rod B, and the cleaner-grid which lies

on the face of one wing of the currycomb is after two or three wraps or convolutions, as at d, rigidly fastened at its end to the other wing, so that there is rigidly attached together 55 a wing of the currycomb on one side and a grid upon the other, the grid having a slight spring action upon the pintle-rod, by reason of the coils of the wire around the said pintle-rod. These grids serve a double purpose, as 60 they not only act as cleaners, as hereinafter described, but they act also as springs to restore the two wings of the currycomb to a flat plane after they have been bent inwardly, as 65 seen in Fig. 1—that is to say, in bending inwardly the wings to fit the curves of the horse it is necessary to slightly deflect inwardly the spring-grids, and their outward tension against the wings causes the wings to immediately straighten out whenever the compression of the hand is relaxed. This enables the 70 currycomb to closely follow and nicely adapt itself to the curves of the horse.

For cleaning the currycomb the wings are 75 forcibly bent backward, as seen in dotted lines in Fig. 2, and then as the grid on one side is rigidly attached to the wing on the other side the turning back of the wings causes their attached grids to pass from the teeth of the two opposite wings and dislodges the matted hair. 80 To facilitate this bending back of the wings, they are each provided at one side, or at both sides, if desired, with projecting thumb-pieces e e', which are seized between the thumb and forefinger to accomplish this result. 85

In constructing the loop or bail-shaped handle it is preferably to be lined or upholstered with leather to render it soft to the hand, and its loop form may, if desired, be widened or extended so as to form a sort of glove or 90 mitten.

I am aware that there have been flexible 95 currycombs and also hinged cleaning devices for the teeth, and I do not claim these features, broadly. My invention is, however, distinctive in the middle articulation of the currycomb upon an axis at right angles to the teeth and the arrangement of the cleaner-grids when mounted upon the middle axis, whereby they not only act as cleaners, but 100 also as springs controlling the flexion of the wings of the currycomb.

Having thus described my invention, what I claim as new, and desire to secure by Letters Patent, is—

1. A currycomb made in two sections hinged together in the middle upon an axis at right angles to the rows of teeth, substantially as described.
2. A currycomb made in two sections hinged together in the middle upon an axis at right angles to the rows of teeth, and springs for restoring these wings to a normal flat plane after having been deflected substantially as described.
3. A currycomb made in two sections hinged together in the middle upon an axis at right angles to the rows of teeth, springs for restoring these wings to a normal flat plane after having been deflected, and a loop or receiver for the hand arranged upon the back of the currycomb to give a purchase for compressing the wings inwardly against the springs substantially as described.
4. A currycomb made in two sections hinged together in the middle upon an axis at right angles to the rows of teeth, combined with two cleaner-grids arranged to turn about the same axis substantially as described.

5. A currycomb made in two sections hinged together in the middle line upon an axis at right angles to the rows of teeth, each of said sections having an attached set of cleaner-grids arranged to lie beneath the teeth of the opposite section substantially as described.

6. A currycomb made in two sections hinged together in the middle upon an axis at right angles to the rows of teeth, and two sets of cleaner-grids attached, one to each currycomb-section, and wound about the axis so as to act also as springs for controlling the movement of the currycomb-sections substantially as described.

7. A currycomb made in two sections hinged together in the middle upon an axis at right angles to the rows of teeth, two sets of cleaner-grids attached to the said sections and arranged to turn about the same axis, and thumb-pieces attached to the hinged sections to permit their convenient deflection in cleaning substantially as described.

CHARLES E. HERSHBERGER.
